VENDING-MACHINE.

1,114,818.

Specification of Letters Patent. Patented Oct. 27, 1914.

Application filed February 13, 1913. Serial No. 748,128.

To all whom it may concern:

Be it known that I, WELCOME F. SWEET, a citizen of the United States, residing at St. Louis, Missouri, have invented a certain new and useful improvement in Vending-Machines, of which the following is a full, clear, and exact description, such as will enable others skilled in the art to which it appertains to make and use the same, reference being had to the accompanying drawings, forming part of this specification, in which—

Figure 1 is a perspective view of a vending machine of my improved construction. Fig. 2 is a vertical section taken lengthwise through the center of the machine or approximately on the line 2—2 of Fig. 1. Fig. 3 is a detail sectional view showing a ratchet and pawl connection forming a part of the operating mechanism of the machine. Fig. 4 is an enlarged vertical section taken approximately on the line 4—4 of Fig. 2. Fig. 5 is a detail elevational view of the upper portion of the coin chute, and showing contiguous parts of the operating mechanism. Fig. 6 is a vertical section taken approximately on the line 6—6 of Fig. 5. Fig. 7 is a detail elevational view of an eccentric and locking pawl forming a part of the actuating mechanism of the machine.

My invention relates generally to new and useful improvements in vending machines, and more particularly to a machine designed and utilized for vending short-term accident insurance policies.

There are at present a number of accident insurance companies which make a specialty of issuing accident insurance policies to travelers, and which policies are good for a limited period of time; for instance, one, two or three days, and at present these policies are usually sold by railway and steamship ticket agents.

I propose to provide a comparatively simple, compact machine which can be positioned on a counter or stand; and which machine will deliver an insurance policy upon the insertion of a coin of proper value and the manipulation of certain mechanism by the person who deposits the coin in the machine.

Among the principal objects of my invention are, to provide a comparatively simple, inexpensive machine having a minimum number of parts so as to reduce the liability

of the machine getting out of order and becoming inoperative, to provide a machine which will require little operation on the part of the person who deposits a coin in payment for a policy, to provide means for the throwing out of under-sized coins which are inserted in the machine for the purpose of operating the same, and further, to provide means for delivering a policy to a purchaser or person who places a coin of proper denomination in the machine and operates the same and at the same time to maintain within the machine a duplicate copy of the policy, thereby maintaining a complete record of all the policies delivered by the machine.

To the above purposes my invention consists in certain novel features of construction and arrangement of parts hereinafter more fully described and claimed.

Referring by numerals to the accompanying drawings, 10 designates the housing of the machine, the same being approximately rectangular in shape, ornamented as desired, and a portion of the top plate or wall 11 being slightly inclined. Formed in the inclined top wall or plate 11 is an opening which is normally closed by a door 12, the same being provided with a glass plate 13, and the upper edge of this door is hinged to the plate 11. Fixed to the right hand upper corner of this door 12 and occupying a position within the housing 10 adjacent to the right hand wall thereof is a weighted quadrant plate 14. Located within the housing immediately below the glazed door 12 is a plate 15 over which passes the sections of paper on which the insurance policies are printed. Journaled at the ends of the plate 15 are small rollers 16 over which passes a transfer ribbon 17, the same occupying a position on the plate 15 between the two sections of paper on which the policies are printed. From the rollers 16 the transfer ribbon extends downward on suitable rollers 18 journaled in bearings on the sides of the housing 10 near the bottom thereof. Fixed on the end of one of these rollers is a beveled pinion 19 which meshes with a corresponding beveled pinion 20, which latter is mounted on a stud 21 and is provided on its edge with a series of ratchet teeth 22.

Journalized in suitable brackets such as 23 in the forward portion of the housing 10

is a spindle 24 which carries a roll of paper 25 on which is printed the policies that are delivered to the purchasers, and journaled in suitable brackets such as 26 to the rear 5 of the brackets 23 is a spindle 27 carrying a roll of paper 28 on which is printed duplicate copies of the policies. The web of paper from the roll 28 passes upward and thence rearward over the plate 15 beneath 10 the transfer ribbon 17, and the web of paper from the roll 25 passes rearwardly over the transfer ribbon 17 and thence rearwardly to the point of exit from the housing. By such arrangement a name, date and other 15 data written on the policy by the purchaser when the door 12 is opened is transferred onto the web of paper from the roll 28, thereby providing copies of all of the policies issued, and which copies are maintained 20 within the machine. A spring-held frame 29 is pivotally connected to the brackets 23 and carries a friction roller 30 which normally engages the surface of the roll 25 to hold the same against over-movement, when 25 the machine is actuated. A corresponding frame 31 is pivotally mounted on the brackets 26 and carries a friction roller 32 which normally bears against the surface of the roll 28. Located in the upper right hand 30 corner of the housing is a pair of plates 33 and 34 which are spaced apart a distance slightly greater than the width of the proper coin utilized for operating the machine, and leading into the space between these plates 35 through the top of the housing 10 is a short coin chute 35. Formed integral with the lower edge of the plate 33 immediately below the chute 35 is a horizontally disposed ledge 36, and arranged to slide freely 40 through the plate 33 immediately above this ledge is a pin 37 having a beveled inner edge, and which pin is carried on the free end of a very light spring 38, the opposite end of which is fixed to the plate 34. The 45 inner plate 33 immediately above the ledge 36 and in front of the pin 37 is cut away to form an opening 39, and immediately above said opening the plate 33 is extended inward to form a pair of oppositely disposed points 50 40, the space between which is slightly less than the diameter of the coin required to operate the machine.

Formed in the plates 33 and 34 immediately above the opening 39 are horizontally disposed slots 41, and communicating therewith at one end are curved slots 42. Formed in the plate 34 and extending upward from the point where the horizontally disposed slot 41 meets the curved slot 42 in 55 said plate is a curved slot 43. Arranged to move lengthwise through the slots 41 is a roller 44, and a corresponding roller 45 is arranged to traverse the curved slots 42. Connecting the trunnions of these rollers 60 44 and 45 outside the plate 34 is a link 46,

and connecting the trunnions of said rollers outside the plate 33 is an inverted U-shaped link 47. Formed in the plate 33 immediately above the opening 39 and the horizontally disposed slot 41 is an opening 48. Leading 70 from the opening 39 downward and thence forward through the housing 10 to a pocket 49 on the front wall thereof is a coin chute 50 which is for the purpose of returning to a would-be purchaser of a policy an undersized coin or a coin of less diameter than the proper coin required for operating the machine. Leading from the space between the plates 33 and 34 and beneath the curved slots 42 is a short coin chute 51, the lower 75 end of which communicates with a vertically disposed tube 52, which latter is adapted to receive and contain the proper coins which have been utilized for actuating the machine. Coins, on passing into the tube 52, pile up one on top of the other, and thus if a person operates the machine with a counterfeit coin of proper size or with a slug which is equal in size to the proper coin, the person having charge of the vending 80 machine can readily ascertain, by counting the coins, which policy was delivered by the machine as a result of the insertion of the counterfeit coin or slug for the reason that the coins piled up within the tube 52 correspond with the policies issued from the machine. 85

Fulcrumed to the top plate of the housing adjacent to the plate 13 is a hand lever 53, the lower end of which is pivotally connected to the trunnion of the roller 45, and thus, as the projecting portion of said hand lever is manually engaged and pulled forward, the roller 45 will be moved through the curved slots 42, and the roller 44 will be moved through the horizontally disposed slots 41. Fulcrumed on a stud 54 projecting inwardly from the right hand side wall of the housing is a lever 55 on the rear end of which is journaled a roller 56, the same occupying a position in the slot 43. The opposite end of this lever is provided with a lug 57 which normally engages against the lower end of the quadrant plate 14, thereby locking the door 12 in its closed position, 90 and the top of this lug 57 is curved so as to bear against the curved edge of said quadrant plate when the door 12 is open. Projecting inwardly from the right hand side wall of the housing is a pair of bearings 58, and arranged to slide therethrough is a rod 59 in the upper portion of which is formed a notch 60. Located on the lower portion of this rod 59 is a collar 61, and located on said rod between said collar and the lower 95 one of the bearings 58 is a compression spring 62. Pivotally connected to the rear end of the lever 55 is the upper end of a link 63, the lower end of which is bent laterally 100 to form a bearing 64 which slides freely 105

upon the rod 59. Fixed to this link 63 is the upper end of a flat spring 65, and carried thereby and projecting through openings formed in the link 63 are pins 66 and 67. The pin 67 normally bears against the surface of the rod 59, and when said rod is moved downward, said pin 67 is adapted to engage in the notch 60 in said rod. Connected to the rear end of the lever 55 is one end of a retractile coil spring 68, the opposite end of which is attached to a fixed pin, said spring normally drawing the rear end of the lever downward so that the roller 56 is maintained in the lower portion of the slot 43. Seated in the right hand wall of the housing 10 and projecting inwardly therefrom is a stud 69, and loosely mounted thereon adjacent to said right hand wall is a collar provided with a sprocket wheel 70 and a ratchet wheel 71, having a single tooth. Loosely mounted on this stud adjacent to the disk 71 is a collar to which is fixed a gear wheel 72, a cam disk 73 provided on its edge with a lug 74, and a disk 75 provided on its edge with a notch 76 and on its side face with a lug 77. Pivotaly mounted on the side of the gear wheel 72 is a spring-pressed pawl 78, the point of which is adapted to engage the shoulder of the disk 71. The notch or shoulder 76 in the disk 73 is adapted to be engaged by the upper end of the rod 59, and the pin 66 carried by the spring 65 is adapted to be engaged by the lug 77 when the disk 75 is rotated.

Pivotaly mounted on a stud projecting inwardly from the right hand wall of the housing 10 is the lower end of a hand lever 79 which projects upward through a slot 80 formed in the right hand portion of the inclined top of said housing, and connected to this hand lever is one end of a sprocket chain 81 which passes around the sprocket wheel 76, and fixed to the opposite end of this sprocket chain is one end of a retractile coil spring 82; the opposite end of which is fixed to a pin or bracket within the housing 10. Carried by the lower portion of this hand lever 79 is a spring-pressed pawl 83, the point of which is adapted to engage the teeth 22 on the edge of the beveled pinion 21. Formed in the top of the housing at the rear end of the inclined portion thereof is a transversely disposed slot 84 through which the policy passes as it is delivered to the purchaser, and mounted for rocking movement immediately adjacent to this slot is a semi-circular housing 85, the rear edge of which is provided with a knife edge 86, whereby the issued portion of the policy is cut from the web of paper from the roll 25.

Mounted on a spindle 87 carried by the housing 85 is a roller 88, and fixed on the end of this spindle is a pinion 89. Fixed to

the right hand end of the housing 85 is a depending spring-pressed arm 90, the lower end of which carries a roller 91 which bears upon the edge of the disk 73. Normally this roller rests upon the lug 74, thereby holding the housing 85 in position with the knife edge 86 bearing directly upon the plate to the rear of the opening 84, thus closing said opening and making it impossible to tamper with the parts within the machine through said opening. A shaft 92 is journaled in the side walls of the housing below the roller 88, and fixed upon said shaft is a roller 93 which bears directly against said roller 88. The policies issued by the machine pass between the rollers 88 and 93 and pass from thence through the opening 84. Fixed upon the shaft 92 is a gear wheel 94 which meshes with the pinion 89 and the gear wheel 72.

Journaled in a suitable bearing in the right hand side wall of the housing 10 is a sleeve 95, and fixed thereon is a gear wheel 96 which meshes with a pinion 96^a, which latter is journaled on a suitable stud and 90 meshes with the gear wheel 72. Loosely journaled in the sleeve 95 is one end of a spindle 97 on which is wound the copies of the policies issued by the machine, and positioned on the right hand end of this spindle is a disk 98. Positioned between this disk and the gear wheel 96 is one or more bowed leaf springs 99 which form a frictional connection between said gear wheel and the spindle, and which connection permits the spindle to differentially move relative to the gear wheel, which differential movement is necessary to compensate for the increasing diameter of the roll of paper as it is wound onto said spindle during the successive actuations of the machine.

The operation of my improved machine is as follows: Under normal conditions, or while the machine is at rest, the various parts of the mechanism occupy the positions shown in Figs. 2, 4, 5, 6 and 7. It will be understood that suitable directions for operating the machine appear at a suitable point on the outer surface of the housing 11, which directions set forth the purpose of the machine, the character of the policy issued, the denomination of coin to be used, and the manner in which the hand levers are to be manipulated, together with any other necessary instructions or information. A person desiring to obtain a policy drops a coin of the proper denomination into the open upper end of the chute 35, and said coin passes downward between the plates 33 and 34, and finally rests upon the ledge 36 with the opposite sides of said coin directly behind the points 40. (See dotted lines Fig. 5). The weight of a coin of proper size is sufficient to push the pin 37 rearwardly against the resistance offered by 130

the spring 38, and if an under-sized coin or a coin smaller than the one required to operate the machine is inserted in the chute 35, it will, by reason of its under-size and 5 light weight, be forced off the ledge 36 by the spring-pressed pin 37, and will pass between the points 40, thereby dropping into the chute 50 through which it will pass to the pocket 49 at the front of the machine. 10 Thus it will be impossible to operate the machine with a coin smaller than the coin of proper size, and said smaller coin will be returned to the person making the attempt to operate the machine. When a coin of 15 proper size has been deposited in the machine, it rests upon the ledge 36 immediately in front of the roller 44. The operator now engages the handle 53 and pulls the same forward, thereby moving the roller 45 20 through the curved slots 42 and moving the roller 44 forwardly through the horizontally disposed slots 41. This movement of the roller 44 is accomplished by reason of its being connected to the roller 45 by the links 25 46 and 47. During the forward movement of the roller 44 it bears against the coin on the ledge 36, thereby moving said coin forward, and during such movement the forward upper edge of the coin bears against 30 the roller 56 on the rear end of the lever 55, thereby elevating said roller through the slot 43, and consequently, elevating the rear end of said lever 55 and causing the forward end thereof to lower. As soon as the 35 forward end of this lever carrying the lug 57 moves downward a sufficient distance to clear the quadrant plate 14, the weight of said plate will cause the same to swing downward over the top of the lug 57, there- 40 by opening the door 12. The forward portion of the movement of the lever 53 moves the coin from beneath the roller 56, thereby releasing the same, and said coin drops into and through the chute 51 and passes 45 from thence into the tube 52. As soon as the door 12 is opened the person purchasing the policy writes upon the exposed portion of the web from the roll 25 above the plate 15 his name, date and other necessary data, as 50 given in the instructions, and the matter thus written on the top web of paper is transferred by the ribbon or sheet 17 to the web of paper from the roll 28 which remains in the machine and forms a permanent record of all policies issued by the machine.

During the upward movement of the rear end of the lever 55 the link 63 is pulled upward a short distance, during which movement the laterally bent lower end 64 slides upward on the rod 59 until the pin 67 carried by the lower end of the spring 65 drops into the notch 60 in said rod. The operator, after writing the data on the exposed portion of the policy beneath the open door, fol-

lows directions and closes said door, which action swings the plate 14 upwardly and rearwardly beyond the lug 57, and the lever 55 is now returned to its normal position under the influence of the spring 68. As the rear end of this lever is drawn downward the link 63 is moved downward a short distance, thereby carrying with it the rod 59 by reason of the engagement of the pin 67 in the notch 60. This downward movement of the rod 59 draws the upper end thereof out of the notch or shoulder 76 in the edge of the disk 75, and such downward movement compresses, to a slight degree, the spring 62. The upper end of the rod 59, having thus withdrawn from the notch in the disk 75, said disk is free to rotate with the parts 73 and 72 on the stud 69. The operator, after closing the door 12, following directions, engages the projecting portion 85 of the hand lever 79 and pulls the same forward to its limit of movement, and the sprocket chain 81 connected to said hand lever operating on the sprocket wheel 70 rotates the same together with the disk 71 90 upon the stud 69. The pawl 78, carried by the gear wheel 72, engages the shoulder formed in the edge of the disk 71, and, as a result, said gear wheel 72, disk 73 and disk 75 are rotated with the disk 71 and sprocket wheel 70. As soon as the disk 73 is moved a short distance the roller 91 on the lower end of the arm 90 rides off from the lug 74 onto the low portion of the edge of said disk, and under the influence of its spring, said arm 90 is shifted slightly, thereby permitting the housing 85 to rock slightly in its bearings, and as a result, the knife edge 86 is elevated a sufficient distance from the plate against which it normally bears to permit the web of paper forming the policy to issue through the slot 84 as the rollers 88 and 93 are rotated. As the gear wheel 72 is rotated its motion is transmitted to the roller 93 by means of the gear wheel 94, mounted 105 on the spindle 92, and in turn this rotary motion is transmitted to the roller 88 by means of the pinion 89, mounted on the spindle 87. Likewise the rotary motion of the gear wheel 72 is transmitted to the spindle 97 through the medium of the pinions 96 and 96^a, and the carbon copies of the policies issued are thus wound onto said spindle 97 to form a permanent record of all policies issued from the machine. The spindle 97 is loosely mounted in the sleeve 95, but the spring 99 forms a frictional connection between the gear wheel 96 and the disk 98 which is mounted on the spindle 97, therefore causing these parts to rotate simultaneously, yet permitting the spindle 97 to rotate differentially with respect to the gear wheel 96 as the roll of paper increases in size on said spindle. The movement of the hand lever 79 which actuates the chain 81 110

120

125

130

is sufficient to rotate the sprocket wheel 70 and disk 71 one complete revolution, and consequently the sprocket wheel 72, disk 73 and disk 75 make one revolution following an actuation of the handle 79. As the disk 73 completes its revolution the lug 74 is brought into engagement with the roller 91, thereby moving the same outward, and as a result, actuating the arm 90, which movement locks the housing 85 in its bearings and causing the knife edge 86 to move downward onto the adjacent plate in front of the opening 84, thereby cutting off that portion of the policy which is issued through said opening 84 and which is to be received by the purchaser.

During the rotation of the disk 75 the lug 77 carried thereby bears against the end of the pin 66, thereby moving the same and the spring 65 outward away from the link 63, and as a result, the pin 67 is moved out of the notch 60, thereby permitting the rod 59 to move upward under the influence of the spring 62, and the end of said rod bears against the edge of the disk 77, and when the same has completed its revolution the upper end of said rod drops into the notch or shoulder 76 in the edge of said disk, thereby locking the parts against further movement until the machine is subsequently actuated after the insertion of a proper coin. As the hand lever 79 is moved forward the pawl 83 engages the teeth 22 on the edge of the pinion 21, thereby partially rotating the same, and as a result, the roller 18 is partially rotated, thereby slightly shifting the ribbon 17. After the handle 79 has been pulled forward to its limit of movement to bring about the movements just described, said handle is released and it returns to its normal position under the influence of the spring 82, during which return movement the sprocket wheel 70 and disk 71 rotate reversely without affecting the gear wheel 72 and parts fixed thereto, and during this reverse rotary movement of the disk 71 the pawl 78 rides on the edge of said disk and finally drops into position behind the shoulder in the edge of said disk.

A machine of my improved construction is comparatively simple, can be readily operated, is very compact, and occupies but little space upon a desk or counter.

The coins received in payment for issued policies pile up within the tube 52 and as the positions of the coins within said tube correspond with the policies issued by the machine, it will be a comparatively easy matter to ascertain the particular policy issued upon the insertion of a counterfeit coin or a slug equal in size and weight to the coin required for payment of the policy and for operating the machine.

It will be readily understood that minor changes in the size, form and construction

of the various parts of my improved vending machine may be made and substituted for those herein shown and described without departing from the spirit of my invention, the scope of which is set forth in the appended claims.

I claim:

1. In a machine of the class described, a casing having an opening, a shelf below said opening, which shelf forms a support for webs of paper from rolls contained within the machine, a closure for the opening, a quadrant plate carried by said closure, which quadrant plate is positioned within the casing, a lever within the casing, and a lug on the end of said lever, which lug engages the front edge of the quadrant plate to hold the closure in closed position.

2. In a machine of the class described, a housing provided with an opening, a shelf beneath said opening over which shelf webs of paper are adapted to pass, there being a second opening formed in the housing through which one of the webs of paper is adapted to discharge, a pair of rollers mounted within the housing adjacent to the discharge opening for effecting a discharge of the end of the webs of paper through said opening, meshing pinions at the ends of said rollers, whereby the same are simultaneously driven, a driving pinion meshing with the pinions on the lower roller, a sprocket wheel, a ratchet and pawl connection between said sprocket wheel and the driving pinion, a chain operating on the sprocket wheel, a retractile coil spring fixed to one end of the sprocket chain, and a hand lever connected to the other end of said sprocket chain.

3. In a machine of the class described, a casing, having a paper discharge opening, a pair of rollers arranged within the casing and adapted to discharge a web of paper through said opening, means whereby said rollers are simultaneously driven, a semi-circular housing arranged for rocking movement immediately to one side of the discharge opening, which housing incloses the upper one of the discharge rollers, one edge of which housing is sharpened so as to sever the discharged web of paper, and means for effecting a rocking movement of the housing to bring the sharp edge thereof into engagement with the web of paper.

4. In a machine of the class described, a casing having a paper discharge opening, a pair of rollers arranged within the casing and adapted to discharge a web of paper through said opening, means whereby said rollers are simultaneously driven, a semi-circular housing arranged for rocking movement immediately to one side of the discharge opening, which housing incloses the upper one of the discharge rollers, one edge of which housing is sharpened so as to sever the discharged web of paper, an arm fixed

6 to one end of said housing, which arm projects downwardly into the machine housing, and means within the machine housing for engaging the lower end of said arm to effect
 5 a rocking movement of the semi-circular housing and bring the sharp edge thereof into contact with the paper at the discharge opening.
 5. In a machine of the class described, a
 10 casing having a paper discharge opening, a pair of rollers arranged within the casing and adapted to discharge a web of paper through said opening, means whereby said rollers are simultaneously driven, a semi-
 15 circular housing arranged for rocking movement immediately to one side of the discharge opening, which housing incloses the upper one of the discharge rollers, one edge of which housing is sharpened so as to sever
 20 the discharged web of paper, a plate below the discharge opening, which plate is normally engaged by the sharpened edge of the semi-circular housing, thereby closing said discharge opening, means within the ma-
 25 chine housing for rocking the semi-circular housing so as to withdraw the sharpened edge thereof from the plate to permit the discharge of paper between said plate and the sharpened edge of said semi-circular
 30 housing, and which last mentioned means also effects a rocking movement of the hous-

ing to bring the sharpened edge thereof into engagement with the plate to sever the section of paper which has passed through the discharge opening.

35 6. In a machine of the class described, a casing having a paper discharge opening, a pair of rollers arranged within the casing and adapted to discharge a web of paper through said opening, means whereby said 40 rollers are simultaneously driven, a semi-circular housing arranged for rocking movement immediately to one side of the discharge opening, which housing incloses the upper one of the discharge rollers, one edge 45 of which housing is sharpened so as to sever the discharged web of paper, an arm fixed to one end of the semi-circular housing and projecting downwardly into the machine, a roller on the lower end of said arm, 50 an eccentric disk, the edge of which bears against said roller, and means for simultaneously actuating the feed rollers and the eccentric disk.

55 In testimony whereof I hereunto affix my signature in the presence of two witnesses, this 10th day of February, 1913.

WELCOME F. SWEET.
